(57) **CLAIM**

The ornamental design for a split top jewelry box, as shown and described herein.

DESCRIPTION

FIG. 1 is a perspective view of my split top jewelry box shown in solid line in the open position with the phantom line showing aspects which are not part of the design being claimed therein;

FIG. 2 is a front perspective view of the split top jewelry box shown in FIG. 1 but in the closed position, the phantom lines being for illustrative purposes only;

FIG. 3 is a bottom view of the split top jewelry box shown in FIG. 2;

FIG. 4 is a top view of the split top jewelry box shown in FIG. 2, the phantom lines being for illustrative purposes only.

FIG. 5 is a right side elevational view of the split top jewelry box shown in FIG. 2 with the left side elevational view being a mirror image thereof; and,

FIG. 6 is a front view of the split top jewelry box shown in FIG. 2 with the rear view being a mirror image thereof with the phantom lines being for illustrative purposes only.
